UNITED STATES PATENT OFFICE

165,747

ELECTRIC FOOD MIXER

Clark H. Gemmill, Chicago, Ill.; City National
Bank and Trust Company, administrator of
Clark H. Gemmill, deceased

Application June 20, 1950, Serial No. 10,638

Term of patent 14 years

(Cl. D44—8)

To all whom it may concern:

Be it known that I, Clark H. Gemmill, a citizen of the United States, residing at Chicago, in the county of Cook, and State of Illinois, have invented a new, original, and ornamental Design for Electric Food Mixer, of which the following is a specification, reference being had to the accompanying drawing, forming a part thereof.

In the drawings:

Fig. 1 is a perspective view of an electric food mixer, showing my new design;

Fig. 2 is an end elevation; and

Fig. 3 is a plan view.

Fig. 4 is a sectional view taken along line 4—4 of Fig. 2 and showing the lower aspect of the design on an enlarged scale.

The essential features of the design are shown in full lines.

I claim:

The ornamental design for an electric food mixer, as shown and described.

CLARK H. GEMMILL.
